UNITED STATES PATENT OFFICE.

WALTER L. PIERCE, OF GALESBURG, ILLINOIS.

TIE-TAMPING MACHINE.

1,180,605.

Specification of Letters Patent. Patented Apr. 25, 1916.

Application filed November 30, 1915. Serial No. 64,264.

To all whom it may concern:

Be it known that I, WALTER L. PIERCE, a citizen of the United States, and resident of Galesburg, in the county of Knox and State 5 of Illinois, have invented a new and useful Tie-Tamping Machine, of which the following is a specification.

My invention relates to machines for tamping the ballast at the sides of and underneath railway ties.

One of the objects is to provide a portable machine adapted to accomplish the indicated operation efficiently and with great rapidity.

Another object is to provide for self-propulsion of the machine.

A further object is to tamp the ballast simultaneously at both sides of a tie.

Minor objects will presently appear. Some of these will be obvious and others 20 specifically pointed out.

The principal end and object of the invention may therefore be said to be to generally improve the construction and to increase the capacity, utility and efficiency of devices of 25 this nature.

In the accompanying drawings, which illustrate a preferred embodiment of my invention: Figure 1 is a side elevation, one of the track-rails partly broken away and the proximal block 9 not shown; Fig. 2, an enlarged detail of the gear-shift mechanism; Fig. 3, an enlarged detail of one of the yielding legs and parts co-operating therewith; Fig. 4, a top plan of the rear frame and the 30 elements carried thereby; Fig. 5, an enlarged detail, showing especially the shaft-bearings and means for supporting them; and Fig. 6, an enlarged detail of the center bearing-block.

Considering said drawings in detail and referring to each element and, where necessary, to each part thereof, by a distinguishing numeral, uniformly employed, 2, 2 indicate railway rails secured on ties 3 by the 40 usual spikes 4.

5, 5 indicate track-wheels mounted on an axle 6 operating each in a journal-box 7 sustained by a frame-box 8.

8' designates a centrally arranged frame-

50 bar.

9, 9 indicate bearing-blocks secured each by bolts 10 to one of the bars 8.

11 indicates a centrally arranged bearing-block secured by bolts 12 to the bar 8'.

55 13, 13 designate journal-boxes suitably mounted on and secured to the blocks 9.

Each oppositely arranged pair of the boxes 13 receives the ends of a multiple-crank shaft 14, 14^a the middle crank-arm 14' of each of which is mounted in a bearing-box 60 15 secured on the block 11. The arms of the shafts 14, 14^a are oppositely arranged, whereby when one is rising the other is descending. Therefore, for the purposes of this specification each of said crank-shafts will, at times, 65 be termed a "compound" multiple crank-shaft, in order to distinguish from a multiple crank-shaft in which all the arms are directed alike.

16 designates a drive-shaft one end of 70 which is mounted in a bearing 17 secured on one of the blocks 9, its other end mounted in a bearing 18 in the center-block 11, and 19 indicates a like drive-shaft mounted in a bearing 20 in the other block 9 and in the 75 bearing 18.

21 indicates a shaft mounted at its ends in bearings 22 in the blocks 9 and at its mid-length in a bearing 23 in the block 11.

23^a designates a shaft the ends of which 80 are mounted in bearings 24 in the frame bars 8 and its midlength in a bearing 25 in the bar 8', as shown clearly in Figs. 5 and 6.

Mounted by means of a spline 26, to slide longitudinally of and to rotate with the 85 shaft 16 is a drive-pinion 27 adapted, by means of a shift-yoke 28, to be thrown into or out of engagement with a crank-shaft-driving spur 29 fixed on the shaft 14; and mounted by means of a spline 30, to slide 90 longitudinally of and to rotate with the shaft 19 is a drive-pinion 31 adapted, by means of a shift-yoke 32, to be thrown into or out of engagement with a crank-shaft-driving spur 33 fixed on the shaft 14^a. Now 95 see Fig. 3. On each arm 34 of the crank shafts 14, 14^a is mounted a journal-box 35 provided with an internally threaded socket 36 which is engaged by the foot of a connecting-rod 37 the headed end of which seats 100 in a tubular leg 38 provided with a top having an axially arranged central aperture of sufficient size to permit movement of the rod 37 but sufficiently small to retain the headed end of said rod. 39 indicates a coil 105 spring embracing said rods and arranged intermediate said socket and leg. The spring is shown in said figure as fully compressed. It will be noted that the legs, because of being mounted on the compound or oppositely-directed-arm shafts 14, 14^a, will be in sets, 110 each set rising as the other descends.

Pivoted to oscillate on the shaft 21 is a series of rocker-links 40, the outer end of each of which is pivotally connected to the lower end of one of the legs 38 by means of a pin 41 or in any other suitable manner. The upper end of a curved tamping-bar 42 is pivotally connected, by means of one of the pins 41, to each of said legs, and each bar is provided with a transversely arranged foot 43. Pivotedly mounted on the shaft 23 is a series of rocker-links 44, their outer ends pivotally connected at 45 each to one of said bars 42. Preferably the links 40 and 44 are arranged in parallelism, for a purpose presently described.

21' designates spacers on the shaft 21, and 23' indicates spacers on the shaft 23.

Pivoted at 46 to the frame-bars 8 are the side-bars 47 of a tractor-frame mounted on 20 axles 48 supported on track wheels 49, 50. An engine 51 or other source of power is mounted on said frame and drives a drum 52 which actuates a belt 53 which embraces a drive-pulley 54 fixed on the shaft 16. Said 30 drum drives also a crossed belt 55 which embraces and drives a pulley 56 fixed on the shaft 19. It will be evident that, due to the crossed belt 55 the pulleys 54 and 56 rotate in contrary directions and that, therefore, 30 the movement of the oppositely directed tamping bars 42 and feet 43 are both toward the tie, but on opposite sides thereof.

57 designates a friction-disk secured on the drum 52, and 58 indicates a friction 35 wheel driven thereby and fixed on an inclined shaft 59 journaled in a bearing 60 and carrying a bevel-wheel 61 which meshes with and drives a bevel spur 62 fixed on the wheel 50.

40 63 indicates a lever pivoted to the shaft 59 and adapted to move the friction-wheel 58 and bevel-wheel 61 into and out of operative positions. The structural peculiarities of the elements numbered 47 to 63 inclusive are immaterial, are not specifically claimed herein, and require no explicit description herein.

The operation: Assume the engine 51 to be driving the drum 52 and thereby the belts 53-55 and pulleys 54, 56 to thereby actuate the shafts 16 and 19 and thereby the pinions 27 and 31 respectively. These pinions transmit motion through the spurs 29, 33 to the crank-shafts 14, 14^a and they to the legs 38 and thereby to the tamping-bars 42 and feet 43. The rocker-links 40, 44 cause the pins 41, 45 to move in arcs, and the movements thereof and of the tamping-bars are as shown by dotted lines in Fig. 1. Should one of the feet 43 strike the tie or any other obstruction the spring 39 will yield against the force exerted by the crank-arm, eliminating danger of breakage. The ballast will be tamped evenly at both sides of the tie, and in a manner superior to that done

manually, for the pressure on both sides of the tie is simultaneous and even, while that of hand-tamping is necessarily the contrary.

To throw either side of the machine into or out of operation the proper one of the shift yokes may be slid in its bearings 70 (Fig. 2) to move the adjacent driving pinion 27 or 31 into or out of gear with the spur wheel with which it was meshed. The machine may be propelled by means of the 75 engine, the drum 52, friction wheel 58, shaft 59, and bevel-gear 61, 62, and this propelling mechanism may be thrown into or out of operative positions by means of the lever 63. The friction wheel 58 is shown as in 80 neutral or inoperative position.

For transportation from place to place the rear frame and all parts secured thereto may be swung forwardly on the pivot 46 onto the forward frame, whereon they may 85 be carried.

For the purposes of this specification each of the two forward and each of the two rear sets of tamping means may be termed a "gang".

It has not been thought either necessary or best to encumber this specification and the accompanying drawings with illustrations of modifications which are not essential to the invention, viewed in its broadest 95 aspect, for numerous such changes would, after the preceding disclosures, present themselves to a skilled mechanic.

I claim as my invention:

1. In combination, a drive-shaft, a pulley, 100 means for driving it, a second drive-shaft, means for driving it in a direction contrary to that of the one first recited, a driving-pinion on the first recited shaft, a spur-wheel normally in mesh with said pinion, 105 means for throwing said pinion and spur-wheel into or out of engagement, a driving-pinion on the second recited shaft, a spur-wheel normally in mesh therewith, means for throwing them into or out of engagement, 110 a plurality of crank-shafts driven each by one of said spur-wheels, and gangs of tamping-elements driven each by one of said spur-wheels.

2. In combination, a pair of multiple- 115 crank shafts, their axes arranged in substantial parallelism, means for driving them in opposite directions, legs pivoted on each of said shafts, tamping-elements pivoted one to each of said legs, a rocker-arm shaft, 120 rocker-arms pivoted thereon and pivotally engaged with said legs, a second rocker shaft, and rocker-arms pivoted thereon and pivotally connected with said tamping elements.

3. In a tamping-machine, a crank-shaft, a leg, a journal-box mounted on said shaft and having a socket, a rod secured in said socket, a hollow leg reciprocable on said rod, a spring embracing said rod and arranged 130

intermediate said socket and leg, and a tamping element connected with said leg.

4. In combination, a drive-shaft, a pulley, a second drive-shaft, means for driving it in a direction contrary to that of the one first recited, a driving-pinion on the first recited shaft, a spur-wheel normally in mesh with said pinion, shifting means for throwing said pinion and spur into or out of engagement, a driving-pinion on the second recited shaft, a spur-wheel normally in mesh therewith, shifting means for throwing them into or out of engagement, a crank-shaft having oppositely arranged crank-arms, driven by one of said spurs, a crank-shaft having oppositely arranged crank-arms and driven by the other spur, and

tamping elements carried one on each arm of each of said crank-shafts.

5. In a tamping machine, a crank-shaft, 20 a leg actuatable thereby, a tamping-bar, a pin pivotally connecting said leg and bar, and parallel rocker-arms one of which is pivoted to said leg and the other to said pin.

6. In a tamping machine, a crank-shaft, 25 means for actuating it, a leg actuatable by said shaft, a tamping bar connected to and driven by said leg, and parallel rocker-arms adapted to guide and control the movements of said leg and bar. 30

In testimony whereof I hereto affix my signature this 12th day of November, 1915.

WALTER L. PIERCE.
